(57) **CLAIM**

The ornamental design for a slide rail, as shown and described.

DESCRIPTION

FIG. 1 is a front elevational view of a slide rail showing our new design.

FIG. 2 is a rear elevational view thereof.

FIG. 3 is a right side elevational view thereof.

FIG. 4 is a left side elevational view thereof.

FIG. 5 is a top plan view thereof.

FIG. 6 is a bottom plan view thereof.

FIG. 7 is a cross-sectional view thereof, taken along line 7-7 of FIG. 1.

FIG. 8 is a front, top, and right side perspective view thereof.

FIG. 9 is an enlarged reference view thereof, taken along line 9-9 of FIG. 1.

FIG. 10 is an enlarged reference view thereof, enlarging an area marked 10 in FIG. 9.

FIG. 11 is an enlarged right side elevational view thereof.

FIG. 12 is an enlarged left side elevational view thereof.

FIG. 13 is a perspective view thereof, showing the slide rail in use in a first alternate position; and,

FIG. 14 is a perspective view thereof, showing the slide rail in use in a second alternate position.
